FUEL FEEDING MECHANISM

Thomas A. Banning, Jr., Chicago, Ill., assignor,
by mesne assignments, to Borg-Warner Corporation, Chicago, Ill., a corporation of Illinois

Application July 17, 1936, Serial No. 91,089

27 Claims. (CL 123—140)

My invention relates generally to internal combustion engines and more particularly to controlled fuel feeding mechanism therefor, it being an object of my invention to provide a new and improved mechanism of this character which insures economical and efficient operation of the internal combustion engine with which it is associated.

Another object of my invention is to provide a fuel feeding and control mechanism for an internal combustion engine in which the speed of the engine is controlled by manually governing only the quantity of air supplied to the engine while the quantity of fuel supplied is automatically controlled in accordance with engine operating conditions.

Another object of my invention is to provide a new and improved mechanism for varying the amount of fuel delivered to the engine cylinders in accordance with changes in the load upon the engine as reflected by the compression developed in the individual compression chambers during the working or compression stroke and as measured by a compression responsive element.

A further object of my invention is to provide such a load controlled mechanism with means for modifying the operation thereof for changes in the engine temperature.

Still another object of my invention is to provide such a load controlled mechanism with means for modifying the operation thereof for changes in the engine speed.

Another object of my invention is to provide a mechanism of this character which is so constructed and assembled that it may be conveniently attached to an internal combustion engine to fit over the manifold thereof in such a manner that the moving parts thereof may be directly connected to some rotating part of the internal combustion engine to be driven thereby.

Another object of my invention is to provide a mechanism of this character having fuel pumping means wherein the intake suction of the engine is unable to affect the flow of fuel from the fuel pumping means to the intake except at such times as the operator purposely connects the fuel line to the suction side of the throttle in the intake for priming purposes.

Another object of my invention is to provide means for such a fuel feeding mechanism whereby the timing of the feeding of fuel to the cylinders is advanced in accordance with the advance in firing timing upon increase in engine speed.

Another object of my invention is to provide means for such a fuel feeding mechanism where-

by the communication between the individual compression passages and compression responsive means is advanced in accordance with the advance in firing timing upon increase in engine speed.

Another object of my invention is to provide such a mechanism with manual means for controlling the same independently of the said modifying mechanisms.

Other objects and advantages will become apparent from the following specification and accompanying drawings, in which:

Fig. 1 is a cross sectional view of an internal combustion engine with an embodiment of my invention, shown in side elevation, attached thereto.

Fig. 2 is a cross section of an assembled unit embodying mechanisms operable in accordance with the principles of my invention.

Fig. 3 is a cross section taken on the line 3—3 of Fig. 2.

Fig. 4 is a cross section taken on the line 4—4 of Fig. 2.

Fig. 5 is a perspective view of a pump plunger operating bracket, and

Fig. 6 is a cross section taken on the line 6—6 of Fig. 2.

It is to be understood that the disclosure herein is merely for purposes of illustration and may be modified without departing from the spirit and scope of my invention as defined in the appended claims.

Combustible mixture is supplied to the engine by a controlled fuel feeding mechanism and an air regulating device, the speed of the engine being governed by manually regulating only the quantity of air supplied to the engine while the quantity of fuel supplied thereto is controlled automatically in accordance with engine operating conditions. The invention utilizes generally an air supply and regulating means therefore, a controlled fuel feeding mechanism generally designated A (see Fig. 1), and automatic control means for the controlled fuel feeding mechanism. The fuel feeding mechanism is primarily controlled in accordance with variation of load on the engine through means therein, generally designated B (see Fig. 2) which means is responsive to the compression within the cylinders of the engine. This load control, moreover, is modified in accordance with engine temperature through means in the fuel feeding mechanism generally designated C and in accordance with engine speed through means therein generally designated D. The operation of the fuel

feeding mechanism may be further modified by manual means generally designated E.

For purposes of disclosure, the invention is here illustrated as applied to an internal combustion engine having a cylinder block 10 with a plurality of cylinders 11, only one of which is here shown, each having a piston 12 reciprocable therein. Secured over the cylinder block 10 is a cylinder head 13 having a recess in its inner face 10 for providing a compression chamber 14 for the cylinder 11. Combustible mixture is supplied to the cylinder through an intake manifold 15, an air inlet 15a, and an intake passage 17 in the cylinder block controlled by an intake valve 18. 15 The combustible mixture is fired by a spark plug 19 extending through the cylinder head and into the compression chamber 14, and the exhaust gases are conducted away by an exhaust manifold 20 connected to the combustion chamber in a manner not shown. The engine is cooled by water jackets 22 and 23 communicating with a pipe 24 leading to a radiator, not shown. Extending upwardly above the cylinder block is a casing 25 housing a distributor drive shaft having a gear 26 fast thereon for driving engagement with a suitable rotating part of the fuel feeding mechanism.

The invention in its preferred form is embodied principally in the previously mentioned fuel feeding mechanism A which is mounted on the engine by a bracket 27 and bolts 28 and 29. This mechanism includes a housing which comprises generally a cap member 30, an intermediate casing 31, a lower casing 32 and a pump casing 33. The lower casing 32 has a hand hole in the side thereof closed by a flanged cover 32a, certain adjustments to be described presently being accessible through said hand hole.

By reference to Fig. 1 it will be seen that the controlled feeding mechanism has generally the shape of an inverted L, the horizontal leg thereof, which includes the cap member 30 and the intermediate casing 31, being positioned over the exhaust manifold 20, while the vertical leg thereof extends downwardly beside the manifold. This shape of the mechanism A enables it to be attached to an engine with a conservation of space and also enables it to derive heat from the exhaust manifold. The horizontal leg houses the compression responsive means B, the temperature responsive means C, and the speed responsive means D, while the vertical leg thereof houses a driving mechanism later to be described in detail which drives the fuel pumping mechanism in accordance with the speed of the engine. From the drawings, it will be seen that the lower end of said vertical leg is closed by the pump casing 33.

The air supply means herein consists simply of an air inlet 15a, while the air regulator takes the form of a butterfly valve 16 disposed in said inlet. The valve 16 is adapted for manual control through suitable connections not shown and has exclusive control of all air supplied to the engine cylinders. It will be seen that opening and closing of the valve 16 will increase and decrease respectively, the compression pressure in the compression chamber 14 and this change in compression pressure will control the quantity of fuel fed to the engine by the fuel feed mechanism in a manner presently to be described.

In order that fuel may be positively pumped in metered quantities in timed relationship with the firing order of the cylinders, I provide a fuel supply mechanism in the pump casing 33 which

in the present embodiment comprises a plurality of plungers 34 having cut-away portions 35 therein and having upwardly and transversely extending arms 36. These plungers are adapted to reciprocate and oscillate in cylinders 37 located annularly in the pump casing 33, there being one plunger and plunger cylinder for each engine cylinder. The pump casing 33 has a duct 38 and a port 38a therein for providing communication with a suitable fuel supply and to which is connected the fuel supply conduit 39. This pump casing also has a plurality of radially extending channels 40 connected with the duct 38, each channel intercepting one of the plunger cylinders 37 and connecting with one of a plurality of ports 41 in the periphery of said casing. One of these ports 41 is shown connected to the intake 15 by means of a conduit 42 adapted to provide communication between the port and a fuel injection nozzle 43 in the intake adjacent the passage 17 in the cylinder block. It is to be understood that each port 41 is connected in a like manner to an injection nozzle in the intake adjacent each of the passages 17 communicating with one of the compression chambers in the engine, there being one port 41, one conduit 42 and one nozzle 43 for each of the compression chambers in the engine.

By reference to Figs. 3 and 4, it will be seen that oscillation of the cylinders 34 will put the cut-away portions 35 in successive communication with the channels 40 and the ports 41. As will be more fully described presently, Fig. 4 shows one of the cylinders oscillated into its suction position while Fig. 3 shows the cylinder oscillated into its ejection position. The vertical reciprocation of the plungers 34 serves to pump the fuel through the duct 37 and channels 40 and out of the ports 41 through the respective conduit 42 to the respective injection nozzle 43 40 in the intake 15, from which point it is drawn through the respective channel 17 with air supplied through the air inlet 15a into the respective compression chamber 14.

This combined reciprocatory and oscillatory movement is applied to each of the plungers 34 by means of a wobble plate 44 having brackets 45 secured peripherally thereto as by screws 46 and movable radially for adjustment. Each of these brackets has a diagonal slot 47 therein through which slot an arm 36 of one of the plungers 34 is adapted to extend, it being understood that rocking of the wobble plate with the resultant vertical movement of the brackets will cause reciprocation of the plungers in the plunger cylinders 36, and, due to the diagonal slot, oscillation will also be imparted thereto during this reciprocation. The plungers 34 are adapted to move upwardly while oscillated to the position shown in Fig. 4 whereby fuel is sucked through the respective channels 40 into the plunger cylinders and are then oscillated into a position shown in Fig. 3 whereby downward movement thereof will force the fuel drawn into the respective plunger cylinders out through the respective port 41.

From the foregoing, it will be seen that by the provision of a pumping mechanism of the type here shown the pumping action thereof will not be detrimentally affected by intake suction 70 since intake suction is not communicated to the fuel supply except under priming conditions later to be fully described.

A screw 48 having a ball head 49 is suitably secured in a boss located centrally of the pump 75

casing 33, the head 49 being adapted to serve as a universal mounting for the wobble plate 44, and a socket for receiving the head 49 is formed by a plate 50 attached beneath the wobble plate by means of screws 51. Extending upwardly from the wobble plate 44 is a driving arm 52 through which rocking motion and resulting pumping action are imparted to said wobble plate.

From the foregoing it will be seen that the quantity of fuel pumped by the form of my invention shown herein is dependent upon the length of the stroke of each individual plunger 34 which length is dependent upon the degree of rocking action of the wobble plate 44, this degree of rocking being entirely dependent upon the angularity of the driving arm 52.

Means is provided for driving the fuel pumping mechanism in timed relationship with the speed of the engine, and in the present embodiment of my invention said means includes gears 53 and 54, the gear 53 being rotatably supported as at 56 by a casing 55 mounted on the distributor shaft casing 25 and extending over a portion of the horizontal leg of the fuel feed mechanism A. Gear 53 is in meshed engagement with gears 26 and 54, the latter being keyed as at 57 to the upper end of a shaft 58 whereby rotary motion is transmitted from the engine to said shaft. The top of the cap member 30 and the floor of the intermediate casing 31 are provided with bearings 59 and 60 respectively, which bearings provide a journal for shaft 58. Rotary motion is transmitted to a gear 54 and through shaft 58 to the gear 61 splined as at 62 to the lower end of said shaft. The gear 61 in turn meshes with a gear 63 fixedly secured to the top of a sleeve 63a which rotates in a bearing 64 located in the floor of the intermediate casing 31. Fixedly secured to the lower end of the sleeve 63a for rotation therewith is a block 65 having lugs 66 depending therefrom, which lugs are adapted to pivotally support a cam member 67 as at 67a. The cam member 67 has in turn, pivotally depending therefrom, a sleeve member 68, which sleeve member is adapted to receive the driving arm 52 of the wobble plate 44 and rock the latter when rotary movement is transmitted thereto from the engine by the mechanism just described.

As previously briefly stated, the quantity of fuel supplied to the engine is governed automatically in accordance with engine operating conditions. This automatic control is primarily in accordance with the load on the engine as indicated by the compression within the cylinders of the engine. To this end I have provided compression responsive means for increasing the pumping action of the pump and thus the amount of fuel pumped through the fuel injection nozzles 43 upon increased compression in the engine cylinders, which means in the present embodiment includes a compression cylinder 69 located in the cap member 30 and communicating with a circular valve chamber 70 by a channel 71. This communication through channel 71 is regulable by means of a screw 72 located in the cap member 30 and held in its adjusted position by a lock nut 72a.

The lower portion of the wall of the valve chamber 70 has a plurality of radial channels 73 extending outwardly therefrom and terminating in a plurality of ports 74, each port being connected by a conduit 75 with one of the compression chambers 14 of the engine. The connection here shown between the conduit 75 and the respective compression chamber 14 is an apertured

nut 75a threaded into a seat in the top of said chamber and having said conduit extending therethrough. It is to be understood that each of the ports 74 is connected by a similar conduit 75 to one of the compression chambers of the engine to which the fuel feed device is attached, there being one duct 73, port 74 and conduit 75 for each of the cylinders of the engine.

A rotary valve 76 has a splined connection with the shaft 58 as at 77 and is adapted to be rotated thereby in the valve chamber 70. The peripheral surface of valve 76 has a vertical slot 78 and an annular groove 79 therein, the slot 78 connecting with the groove 79 as shown in Fig. 2. As the shaft 58 rotates the rotary valve 76, the slot 78 thereof communicates successively with each of the ducts 73 while the groove 79 is in constant communication with channel 71 whereby compression in the successive compression chambers 14 is communicated through the conduits 75, 20 ducts 73, slot 78, groove 79 and channel 71 to the compression cylinder 69.

Means responsive to the compression thus conveyed to the cylinder 69 is shown herein as a piston 80 which has control means including a push rod 81 suitably secured thereto as by a nut 83. If desired a cup washer 84 may be secured between the upper surface of said piston and the nut 83 in order to insure a tight seal for said piston. The lower end of push rod 81 abuts the upper surface of a cam block 82, the latter being suitably mounted in a manner to be presently described for vertical movement, and having the upper end of a push rod 83 abutting its lower surface. It will be understood that push rods 81 and 83 and cam block 82 comprise the control means of the embodiment disclosed herein. The push rod 83 is slidably received by the sleeve 63a and has a cam roller 84 rotatably mounted at the lower end thereof adapted to engage a cam surface 85 of the cam member 67. It will be seen that downward movement under the influence of pressure in the compression cylinder 69 is transmitted to the push rod 83 through push rod 81 and cam block 82 and will cause the roller 84 to engage the cam surface 85 whereby the cam member 67 will be pivoted outwardly on lugs 66 which pivotal movement in turn regulates the angularity of the sleeve member 68. The angularity of this member 68 is in turn adapted to regulate the degree of rocking motion of the wobble plate 44 during rotation thereof with member 67 and block 65, since the driving arm 52 is slidably received by the member 68. This downward movement of push rod 83 and consequent pivotal movement of member 67 will result in an increase of the angle between the driving arm 52 and the vertical thereby increasing the displacement of the strokes of plungers 34 in plunger cylinders 37 by the rocking movement of the wobble plate.

A spring member 86 is secured to one side of the block 65 for urging the cam member 67 inwardly and arm 52 through the medium of sleeve member 68 toward a vertical position against the downward movement of the roller 84 under compression pressure transmitted to chamber 69 through the rotary valve 76. This spring 86 has an adjusting screw 87 in the lower extremity thereof lockable in its adjusted position by lock nut 88. A compression spring 89 is positioned in the compression cylinder 69 above the piston 80, its upper end being urged against a plate member 90 which is adjustable by an adjusting screw 91 threadably secured in the upper wall of the 75

chamber 69. Tension of spring 86 is adjusted by the plate so that the piston 80, push rods 81 and 83 and members 67 and 68 are urged against the tension of the spring 86 in order that the spring 86 will not throw the members 67 and 68 inwardly immediately upon the fall in pressure in the chamber 69.

From the foregoing, it will be seen that the pump mechanism is driven by the engine through the medium of shaft 58 and that the rotary valve is also driven by said shaft. Thus the relative location of ducts 73 and ports 74 around the circular chamber 70 and of the plunger cylinders 37 and ports 41 around the pump casing 33 may be determined so that the slot 78 of the valve 76 will communicate with the duct 73 of a particular compression chamber immediately preceding the time when the respective plunger 35 for that cylinder will be moved downwardly in its respective plunger cylinder 37. The result of such an arrangement is that the compression pressure of each particular cylinder is transmitted to the members 67 and 68 in the manner above described, and the length of the stroke of a given plunger 34 will be adjusted in accordance with said compression in timed relationship with the ejection stroke of said plunger.

It is to be understood, however, that while I have disclosed the embodiment of my invention herein as utilizing the compression pressure of the cylinders, the working or firing pressure may under some condition be found more adaptable, the control of fuel feed herein being determined generally by the quantity of air introduced into the cylinders.

Mechanism is also provided for modifying the action of the above described compression control mechanism in accordance with engine temperature by decreasing the amount of fuel supplied upon an increase in engine temperature, and in the present embodiment this mechanism includes a bulb 92 extending into the path of the cooling medium of the engine as it flows through the pipe 24. This bulb contains suitable expandable matter which, when it expands upon any increase in the temperature of the cooling medium, overflows from said bulb through a conduit 93 to a Sylphon 94 whereby the Sylphon is expanded upon such increase in temperature. The Sylphon 94 is suitably secured in the wall of the intermediate casing 31 adjacent the cam block 82. In order that the cam block 82 may be moved horizontally by Sylphon 94, upon expansion and contraction of the latter and in order that this horizontal movement is not impaired by the movement of the block through a plurality of vertical positions, which vertical positions vary from time to time upon movement of piston 80 and push rods 81 and 83, I have provided a pivotal connection between the cam block and the Sylphon through lugs 95 which extend from the inner end of the Sylphon 94 and to which the adjacent end of cam block 82 is pivoted. The remote end of cam block 82 is also pivotally supported by lugs, one of which is shown at 96, extending inwardly from the intermediate casing 31 on each side of the Sylphon, which lugs have pivoted thereto as at 97 the arms of a U-shaped member 98. The bridge of the U-shaped member 98 has a screw 99 threaded therein, which screw has a reduced stem 100 extending through a slideway in the cam block 82. This stem 100 is adapted to hold the block 82 in alignment for its horizontal reciprocation under influence of the Sylphon 94, and it will be

seen that the above described pivotal supporting arrangement for the block will permit free movement thereof vertically under the influence of compression chamber 69 without impairing the horizontal or longitudinal movement thereof by 5 the Sylphon 94.

The block 82 is drilled from the end remote from the Sylphon 94 to receive a compression spring 101, which is coiled around the stem 100 and compressibly held between the shoulder of 10 screw 99 and the wall of the drilled out portion of block 82.

By reference to Fig. 2, it will be seen that cam block 82 is tapered in such a manner that as it is moved to the left under increase in engine 15 temperature and consequent expansion of the Sylphon 94, the aggregate length of push rods 81 and 83 between the piston 80 and the cam member 67 will be reduced, whereby the angularity of driving arm 52 of the wobble plate 44 20 will be reduced due to the tension of spring 86, this reduction in the angularity of arm 52 causing a relative reduction in the length of the pumping strokes of plungers 34. Upon a decrease in the temperature of the cooling medium 25 the expandable matter in bulb 92 will contract thereby reducing the length of Sylphon 94 and permitting the spring 101 to move the cam block 82 to the right of Fig. 2 which movement, due to the angularity of the surfaces of the cam block, will cause an increase in the aggregate length of push rods 81 and 83 between the piston 80 and roller 84. Such an increase in the aggregate length of the push rods, it will be seen, will move the cam surfaces 85 downwardly whereby the 35 angularity of sleeve member 68 and of the driving arm 52 of the wobble plate will be increased due to the pivoting action between members 67 and 68 at 68a. Under such conditions it will be seen that the length of the pumping strokes of 40 plungers 34 will be increased to provide greater quantities of fuel through the control movements of the piston 80 under the influence of compression in the compression chamber 69.

In order that the angularity of the driving 45 arm 52 of the wobble plate 44 may not be affected by centrifugal force during rotation of the driving elements located thereabove, an integral arm 102 depends from the block 65. A lever 103 having a flyball 104 at one end thereof 50 is pivoted to the lower extremity of arm 102 and is operably connected to the member 67 by a link 105. The size of the flyball 104 is determined by the weight of the members 67 and 68 so that it balances them during rotation of the 55 block 65 in such a manner that the downward movement of the flyball during rotation of said block will draw the member 67 inwardly about its pivot 67a to decrease the tendency of the member to pivot outwardly due to centrifugal 60 force during the rotary driving movement of the block 65 and its appurtenances.

Means is also provided for modifying the action of the compression control mechanism in accordance with engine speed by decreasing the 65 quantity of fuel supplied upon increases in engine speed. To this end I have provided a mechanism which in the present embodiment includes a collar 106 having an annular extension 107 at the lower end thereof and from which ears 110 70 depend. This collar 106 is suitably attached to the rotary valve 76 by an annular member 108 secured thereto and having at its upper end an inwardly extending flange 109 embedded into the hub portion of the valve 76 whereby the valve and

the collar 106 rotate with shaft 58 and with one another. A second collar 112 is keyed as at 113 for rotation with the shaft 58 and has radially extending ears 114 to which lugs 115 of flyballs 116 are pivoted as at 117. The lugs 115 have inward extensions to which are pivoted links 111 as at 118, the links 111 in turn having pivotal connection with ears 110. The foregoing linkage is so arranged that upon an increase in the speed of rotation of shaft 58 the flyballs will rise due to centrifugal force and being pivoted at 117 to the keyed collar 112, the links 111 with the flange 107 will be drawn downwardly.

15 The above described movement of the flange 107 will cause like movement in a lever 119 which engages the lower surface thereof and is rockably secured on a shaft 120, the latter being suitably secured to the under surface of the cap member 30 by ears 121. Downward movement of this lever 119 will cause upward movement in a lever 122 similarly mounted on the shaft 120, since levers 119 and 122 are operatively connected through the medium of pins 123 which are engaged by the ends of spring 124 coiled around the shaft 120. The upward movement of lever 122 upon such increase in speed of rotation of the shaft will cause similar upward movement of push rod 81 against the compression in the chamber 69 due to its engagement on the under side of a cross piece 126 fixedly secured to the push rod 81 and held in alignment by an aligning pin 125 which depends from the cap member 30. It will readily be seen that this upward movement 35 of the push rod 81 will permit similar movement of the cam block 82, push rod 83 and cam member 87 under the tension of spring 86 in a manner previously described. It will also be seen that this movement of the foregoing parts will permit 40 sleeve member 68 and driving arm 62 to move toward a vertical position thereby decreasing the length of the pumping strokes of the plungers 34 in the manner previously described. Should the speed of rotation of the shaft 58 be decreased, 45 the quantity of fuel pumped will be increased since flyballs 116 will drop to move the flange 107 and lever 119 upwardly and the lever 122 downwardly, thereby permitting downward movement of push rod 81 under compression in the chamber 69 or under the tension of the spring 89 to increase the angle of driving arm 62 in a manner 50 previously described.

Since the wobble plate 44 is driven by the engine through shaft 58 and since the rotary valve 76 is mounted on said shaft to rotate therewith, it will be seen that because the shaft 58 is driven directly from the engine, the wobble plate 44 and the valve 76 may be driven in exact accordance with the speed of the engine. As previously described, the slot 78 in the valve 76 will communicate successively with the ducts 73 of each cylinder and the wobble plate 44 will cause fuel to be pumped to the respective ports 41 of each cylinder successively, both the valve 76 and the wobble plate 44 operating in exact timing with the firing of the cylinders. However, upon increased engine speed the successive communication between ducts 73 and slot 78 and the injections of fuel into the successive ports 41 must be advanced in accordance with the advance in firing timing which results from an increase in speed of an internal combustion engine. I have provided means for accomplishing this advance in the fuel feed mechanism disclosed herein, which means in the present embodiment of my invention com-

prises splines 77 and 62 in the shaft 58. The splines as shown herein take a spiral form, and by reference to Fig. 2 it will be seen that the curvature of the splines is opposed, the purpose of which will be described presently.

In order that the valve 76 may be moved vertically with respect to shaft 58 and thereby be advanced upon increase in engine speed, the height of the valve 76 is less than the height of the circular valve chamber 70 in which it rotates. As previously explained, the valve 76 is fixedly secured to the shaft 58 for rotation therewith by the spline 77, but it is also adapted to move vertically relative to said shaft and within the confines of the chamber 70. Inasmuch as the spline 77 is spiral in form, it will be readily understood that vertical movement of the valve 76 upon the shaft 58 will cause the former to rotate relative the latter.

This vertical movement is obtained upon change in engine speed for rotatably advancing said valve with respect to said shaft by means of the hereinbefore described flyballs 116 and their connection with the valve through the annular member 108. As previously described, increase in engine speed will increase the rotation of the shaft 58, which increase will in turn cause the flyballs 116 to move upwardly. This upward movement of the flyballs will cause downward movement of the valve 76 due to its connection with the flyballs through links 111, collar 106, annular member 108 and flange 109, whereby the valve and thus the slot 78 therein will be advanced in accordance with the advance in firing timing in the engine. 30 35 25

Likewise, it is necessary to advance the drive mechanism for the pumping means. This advance is accomplished by means which in the present embodiment takes the form of ears 127 integral with the flyballs 116 and having links 128 pivoted thereto. The links 128 are in turn pivoted to radially extending ears 129 on the hub of gear 61. This gear 61 is mounted on shaft 58 similarly to the valve 76, that is, fixedly secured to the shaft for rotation therewith but is adapted to move vertically with respect thereto. Since the spline 62 is also spiral in form and its curvature is opposed to that of spline 71, it will be seen that upward movement of the gear 61 with respect to shaft 58 will cause an advance of the gear relative to said shaft in the same direction as the advance of valve 76 upon downward movement of the latter. This upward movement of the gear 61 is accomplished simultaneously with the downward movement of valve 76 by the upward movement in the flyballs 116 upon an advance in engine speed through the medium of lugs 127, links 128 and ears 129. It is to be understood that this advance in the position of the gear 61 will cause a similar advance in the remainder of the driving mechanism for the pump. A compression spring 130 is coiled around the shaft 58 and is compressively held between the collar 112 and the hub of the gear 61. The purpose of this spring is to urge the gear 61 downwardly on the shaft 58 against the tendency of the gear to move upwardly through the medium of flyballs 116 upon increased engine speed.

By reference to Fig. 2, it will be seen that the teeth of gears 61 are broader than the teeth of gears 62 with which they mesh, the purpose of this construction being to insure against this meshed engagement being broken during vertical movement of the gear 61 with respect to the gear 62. 70

In order that fuel may be pumped to the engine in excessive quantities for choking purposes, I have provided means which in the present embodiment takes the form of a lever 131 pivotally mounted on the cap 30 by an upwardly extending lug 132. One arm of this lever is connected to manually operable means not shown herein, while the lower surface of the other arm engages the upper end of a pin 133 extending through the cap 10 member 30 and secured to the cross piece 126 previously described. Movement of the lever 131 will be transmitted through the pin 133 to cross piece 126 thence to the push rod 81 whereby push rod 83 and members 67 and 68 may be manually controlled to increase the angularity of driving arm 52 of the wobble plate against the tension of spring 86. This increase in the angularity of arm 52 will increase the pumping stroke of plungers 34 and thus the quantity of fuel pumped to 20 the engine cylinders in the manner previously described.

Means is also provided for priming the fuel pump, which means in the present embodiment takes the form of a duct 134 in the pump casing 25 33. This duct 134 connects with one of the plurality of radial channels 40 and communicates with the air inlet 15a on the suction side of valve 16 through a conduit 135. Communication between the intake suction and the channels 40 is 30 controlled by means of a valve 136 which is located in the conduit 135 and has a lever 137 connected with suitable manually controlled means, not shown. When valve 136 is opened by lever 137 suction created in the air inlet 15a will be communicated to the channels 40, to the duct 38 and thence to the liquid fuel supply line 39 whereby fuel will be sucked from the fuel supply into channels 40. Preferably, the connections to the lever 137 run to the control station for the internal 40 combustion engine.

In order to obtain smooth and efficient operation of the wobble plate 44 and plungers 34, I provide a sealed chamber 138 above the pump casing 33 which may be flushed with suitable 45 lubricant. Inverted over the pump casing 33 and fitting within the lower casing 32 is an inverted cup-shaped member 139 having an aperture in the top thereof to permit operation of the sleeve member 68 and driving arm 52. The member 139 50 has an annular member 140 riveted to the top thereof, the members 139 and 140 having secured therebetween the outer peripheral edge of a ring 141 of suitable elastic material, the inner peripheral edge of which is sealed with the top of 55 wobble plate 44 by means of an annular member 142 secured to the wobble plate by means of screws 51.

I have provided means for flushing the chamber 138 with a suitable lubricant which in the present embodiment comprises a cylinder 143 having a connection 144 with the interior of chamber 138. A plunger 145 having a rearwardly extending stem 146 is urged forwardly in the cylinder by means of a compression spring 147. A funnel 148 is connected to the cylinder by a pipe 149. Upon withdrawal of the plunger by the stem 146 lubricant may be admitted to the cylinder forwardly of the plunger through the funnel 148 and pipe 149. Upon release of the stem 146 the 70 plunger will be urged forwardly thereby forcing lubricant into chamber 138.

From the foregoing statement of my invention and description of a preferred embodiment thereof, it will be seen that I have provided means 75 whereby the operation of an internal combustion

engine may be governed by the pressure developed in the cylinders thereof and modified by existing temperature and speed conditions therein. It will also be seen that with such a control the regulation of the air supply will in turn control 5 the fuel supply. Thus the operation of the engine is responsive to the quantity of air supplied to the engine. However, I do not intend to limit the scope of my invention to the use of the controls disclosed herein, it being understood that I 10 also contemplate their use severally or in combination with an internal combustion engine, whereby the economy and efficiency of the engine will be greatly enhanced.

I claim as my invention:

1. In a fuel feed mechanism for an internal combustion engine having cylinders, a fuel pump, a driven element in said mechanism connectible with the engine to be driven thereby and drivingly connected to said pump, a pressure responsive device in said mechanism, means associated with said driven element for establishing communication successively between the compression chambers in the cylinders of the engine and the pressure responsive device, control means operatively connected to said fuel pump and said pressure responsive device for controlling said pump in accordance with compression pressure in said cylinders, and means for varying said compression pressure including air supply means for the cylinders of the engine having a valve member there-in for controlling the passage of air to the cylinders.

2. In a fuel feeding mechanism for an internal 35 combustion engine having cylinders, a fuel supply device for supplying fuel to the cylinders, means for controlling said fuel supply device for increasing the amount of fuel supplied to the cylinders in accordance with an increase in the compression pressure in the cylinders comprising a 40 pressure responsive device and means for establishing communication between said pressure responsive device and the compression chambers of the cylinders when said cylinders are under compression.

3. In an internal combustion engine having cylinders, in combination, an air supply device for said cylinders having a manually operable regulator therein for controlling the quantity of air supplied, and a fuel feeding mechanism having a fuel pump therein, control means for said pump whereby the quantity of fuel pumped thereby is metered, a mechanism for regulating said control means operable to increase and decrease the quantity of fuel in accordance with a corresponding increase and decrease in the amount of air supplied to said cylinders including a pressure responsive device cooperable with the control means, and means forming a passage for establishing communication between said device and the compression chamber portion of said cylinders when the same are undergoing compression.

4. In a fuel feed mechanism for an internal combustion engine, a fuel pump, said fuel pump being adapted to be driven by said engine, compression responsive means, means for establishing communication successively between said cylinders, and the compression responsive means adapted to be driven by said engine to control the output of said fuel pump in accordance with compression developed in said cylinders, air supply means for said cylinders, and valve means in said air supply means for regulating the passage of air therethrough.

5. In an internal combustion engine having 75

cylinders, in combination, an air supply device for the cylinders having an air regulator for controlling the quantity of air supplied, a fuel feeding mechanism having control means therein for 5 governing the quantity of fuel fed thereby, a pressure operated mechanism for regulating said control means to constantly vary the amount of fuel in accordance with the amount of air supplied to the cylinders, and means forming a valved passage for establishing communication between said last named mechanism and the compression chambers of the cylinders to subject said mechanism to the periodic changes in the compression pressure in each cylinder.

15 6. In an internal combustion engine having cylinders, in combination, means for supplying air to the engine, means for controlling the flow of air through said air supply means, and a fuel feeding mechanism for feeding fuel to the engine 10 including control means for regulating the feeding of fuel, compression pressure responsive means for operating said control means so as to increase the fuel feed to the engine as a result of increase in compression pressure, means for communicating pressure from the engine cylinders to said pressure-responsive means when said cylinders are undergoing compression, and a rotating mechanism directly responsive to engine speed for progressively modifying the effect of said 15 pressure-responsive means upon said control means.

20 7. In a fuel feeding mechanism for an internal combustion engine having cylinders, a fuel pump, a sectioned control element operatively connected with said pump at one end and having a piston secured to its other end, a compression cylinder adapted to receive said piston, means for establishing communication between said compression cylinder and the cylinders of said engine during 25 a portion of the cycle of each cylinder whereby pressure created in the engine cylinders during that portion of each cycle thereof will be transmitted to said compression cylinder, said piston with said sectioned control member being adapted 30 to vary the output of said pump in accordance 35 with the movement of said piston within said compression cylinder in response to variations in compression therein created by similar variations of pressure within the engine cylinders, a block 40 having cam surfaces, mounted for horizontal movement between the sections of said control member upon variations in engine temperature whereby the sections are moved toward and away from one another for varying the aggregate length 45 of said control member upon such temperature variations, means for pivotally mounting said block whereby said block may move in a path longitudinally of and with said control member 50 throughout the compression responsive movement thereof and also at substantially right angles to said longitudinal movement upon changes in engine temperature.

55 8. In a fuel feed mechanism for an internal combustion engine having cylinders, fuel pumping means, a shaft in said mechanism connectible with the engine to be driven thereby, a circular valve chamber in said mechanism, radial ducts in the wall of said valve chamber connectible with the compression chamber portions of said cylinders, a rotary valve operable in said valve chamber by said shaft and having a slot therein successively communicable with said ducts during rotation of said valve, a groove in said valve connected with said slot, a cylinder in said mechanism and a pressure responsive piston operable

in said cylinder, a conduit connecting said groove and said cylinder whereby pressure conveyed to said groove is transmitted to said cylinder to operate said piston, and means operatively connected with said piston and said fuel pumping 5 means for regulating the quantity of fuel pumped by said pumping means upon movement of said piston within said cylinder.

9. In a fuel feeding mechanism for an internal combustion engine having cylinders, in combination, a fuel delivery mechanism, a pressure responsive mechanism for varying the output of said fuel delivery mechanism in accordance with pressure developed in the cylinders of the engine, means for establishing communication between 15 said cylinder and said pressure responsive mechanism, temperature responsive means for modifying the effect of said pressure responsive mechanism upon said fuel delivery mechanism in accordance with changes in the temperature of 20 the engine, speed responsive means for modifying the effect of said pressure responsive mechanism upon said fuel delivery mechanism in accordance with variations in the speed of the engine independently of said last named means, and 25 manually operable means for varying the effect of said pressure responsive mechanism upon said fuel delivery mechanism independently of said temperature responsive means and said speed responsive means.

30 10. In a fuel supply system for an internal combustion engine having cylinders and an air supply device for said cylinders with means for controlling the passage of air therethrough, a fuel feeding mechanism having, in combination, a 35 control means for regulating the action of said fuel feeding mechanism, pressure responsive means for regulating said control element, means for communicating pressure from the engine cylinders to said pressure responsive means and 40 mechanism responsive to engine temperature for modifying the effect of said pressure responsive means on said control means.

45 11. In a fuel supply system for an internal combustion engine having cylinders and an air supply device for said cylinders with means for controlling the passage of air therethrough, a fuel feeding mechanism having, in combination, a control means for increasing and decreasing the action of said fuel feeding mechanism, pressure 50 responsive means for regulating said control element in accordance with pressure in the engine cylinders, means for communicating pressure from the engine cylinders to said pressure responsive means and mechanism constantly dependent on various engine speeds for modifying the effect of said pressure responsive means on 55 said control means.

60 12. In a fuel supply system for an internal combustion engine having cylinders and an air supply device with means for controlling the passage of air therethrough, a fuel feeding mechanism having, in combination, fuel pumping means, a control element for said fuel pumping means, pressure responsive means for regulating said 65 control element, means for establishing successive communication between the cylinders and said pressure responsive means in timed relationship with the firing timing of the cylinders, and means for advancing the successive communication between the cylinders and said pressure responsive device in accordance with the advance in firing timing of the cylinders upon increased engine speed.

70 75 13. In a fuel feed mechanism for an internal

- combustion engine having cylinders, fuel pumping means for pumping fuel successively to said cylinders, driving elements for said pumping means including a drive shaft drivingly connectible with the engine and having a gear mounted thereon for rotation therewith, said shaft and said gear being relatively longitudinally movable, pressure responsive means for regulating the quantity of fuel pumped by said pumping means, said pressure responsive means being in successive communication with the compression chambers of the cylinders, a rotary valve for establishing such successive communication mounted on said drive shaft for rotation therewith, said shaft and said valve being relatively longitudinally movable, spiral splines for securing said gear and said valve to said shaft whereby said gear and said valve are rotated relative said shaft upon relative longitudinal movement between said shaft and said gear and valve, and speed responsive means associated with said shaft for obtaining such longitudinal movement upon change in engine speed.
14. In a fuel feed mechanism for an internal combustion engine having cylinders, fuel pumping means for pumping fuel successively to said cylinders, driving elements for said pumping means, said elements being drivingly connectible with the engine, pressure responsive means for regulating the quantity of fuel pumped by said pumping means, said pressure responsive means being in successive communication with the compression chambers of the cylinders, valving means for establishing such communication, said valving means being operable by one of said driving elements, an engagement between two of said driving elements and between said valving means and the driving element by which it is operated whereby axial movement between said driving elements and between said valving means and the driving element by which it is operated will cause an advance in the driving movement of the drive elements for the pump and an advance in the valving operation, and means for causing such axial movement in accordance with increases in engine speed.
15. In an internal combustion engine having cylinders, in combination, an air supply device having means for controlling the passage of air therethrough, and a fuel feed mechanism adapted to feed fuel successively to the cylinders in timed relationship with the firing timing thereof and having a fuel pumping mechanism and control means therefor, pressure responsive means for regulating said control means, means for successively establishing communication between the cylinders and said pressure responsive means in timed relationship with the firing timing of the cylinders, and means for advancing the successive feeding of fuel to the cylinders and the successive communication between the cylinders and the pressure responsive means in accordance with the advance in firing timing of the cylinders upon increased engine speed.
16. In a fuel supply system for an internal combustion engine having cylinders, an air supply device for said cylinders with means for controlling the passage of air therethrough and a fuel feeding mechanism adapted to feed fuel successively to the cylinders in timed relationship with the firing timing thereof having, in combination, fuel pumping means, control means for said fuel pumping means, pressure responsive means for regulating said control means, means for successively establishing communication be-

tween the cylinders and said pressure responsive means in timed relationship with the firing timing of the cylinders, mechanism for modifying the regulating effect of said control means in accordance with the temperature of the engine, mechanism for modifying the regulating effect of said control means in accordance with the speed of the engine, and means for simultaneously advancing the successive feeding of fuel to the cylinders and the successive communication between the cylinders and the compression responsive means in accordance with the advance in firing timing of the cylinders upon increased engine speed.

17. In a fuel feed mechanism for an internal combustion engine having cylinders, in combination, means for pumping fuel to the cylinders, a driven element in said mechanism connectible with an engine to be driven thereby, and being adapted to drive said fuel pumping means, a load responsive control member in said mechanism operatively associated with said fuel pumping means for varying the quantity of fuel delivered to the cylinders thereby, pressure responsive means operatively associated with said control member, means establishing communication between the cylinders and said pressure responsive means whereby the latter may be operated in accordance with the pressure in the cylinders, speed responsive means associated with said driven element operable upon speed changes therein, means for operatively connecting said speed responsive means with said control member, and temperature responsive means operatively associated with said control member for movement therewith throughout its movement by said pressure responsive means, said temperature responsive means being mounted for temperature responsive movement throughout its load responsive movement with said control member.

18. In an internal combustion engine having cylinders, in combination, an air supply device having means for metering the passage of air therethrough, a fuel feeding mechanism including a fuel pump for supplying fuel to the engine, means for governing the fuel supply comprising a control means for said fuel pump, a pressure responsive device for regulating said control means, means for establishing communication between the cylinders and said pressure responsive device, mechanism for modifying the regulating effect of said control means in accordance with the temperature of said engine, and mechanism for modifying the regulating effect of said control means in accordance with the speed of said engine.

19. In a fuel supply mechanism for an internal combustion engine having cylinders, a fuel supply device for supplying fuel to the cylinders, having, in combination, pressure responsive means for varying the amount of fuel supplied to the cylinders in accordance with variations in the amount of air drawn into the cylinders, means for establishing communication between said pressure responsive means and the cylinders, means for modifying the effect of said pressure responsive means in accordance with engine temperature, and means for modifying the effect of said pressure responsive means in accordance with engine speed.

20. In a fuel feed system for an internal combustion engine, the combination of a fuel pumping mechanism having adjustable driving means, driving elements for said fuel pumping mechanism connectible with an engine to which the

- fuel feed system is to be attached, control means for adjusting said driving means, temperature responsive means adapted to regulate said control means and including a cam element movable in response to changes in engine temperature and adapted to vary the aggregate length of said control means during its temperature responsive movement, and speed responsive means operatively connected with said driving elements and movable upon changes in engine speed for further regulating said control means.
21. In a fuel feed system for an internal combustion engine, the combination of a fuel pumping mechanism having adjustable driving means, driving elements for said fuel pumping mechanism connectible with an engine to which the fuel feed system is to be attached, control means for adjusting said driving means, speed responsive means operable with said driving elements and being adapted to regulate said control means upon speed changes in said driving elements, and temperature responsive means operatively connected with said control means and movable upon changes in engine temperature for further regulating said control means.
22. In a fuel feed mechanism for an internal combustion engine, in combination, a control means movable to vary the quantity of fuel fed by the mechanism, temperature responsive means for regulating the movement of said control means in accordance with changes in temperature in the engine to which said mechanism is attached and speed responsive means for regulating the movement of said control means in accordance with changes in speed of the engine to which said mechanism is attached.
23. In a fuel feed mechanism for an internal combustion engine, a rotary valve, a pressure responsive element adjacent said valve, an engine driven element beneath said valve, a pump driving element adjacent said engine driven element and beneath said pressure responsive element and a fuel pump and fuel pump connections beneath said pump driving element, all contained in a substantially inverted L-shaped housing for attachment over the manifold of an internal combustion engine.
24. In a fuel feed mechanism for attachment to an internal combustion engine, fuel feed control mechanisms centered about a pair of axes, one of said mechanisms being longer than the other, an engine driven member comprising the shorter mechanism, said mechanisms being contained in a substantially inverted L-shaped housing for attachment to an internal combustion engine with said shorter mechanism nearer to a rotating part of said engine with respect to said longer mechanism for establishing a driving connection between said longer mechanism and said rotating part of the engine.
25. In combination with an internal combustion engine having a manifold at its side, a fuel feed mechanism for controlling the quantity of fuel delivered to the engine in accordance with engine operating conditions assembled and constructed to be contained in a substantially inverted L-shaped housing for attachment to said engine with one arm parallel to the side of the engine block and adjacent said manifold while the other arm is parallel to the top of said engine block and adjacent said manifold.
26. In a fuel supply system for an internal combustion engine having cylinders and an air supply device with means for controlling the passage of air therethrough, a fuel feeding mechanism having, in combination, fuel pumping means, a control element for said fuel pumping means, pressure responsive means for regulating said control element, means for establishing successive communication between the cylinders and said pressure responsive means in timed relationship with the compression in said cylinders.
27. The combination with an internal combustion engine operating on a definite cycle and having a plurality of cylinders operating in a definite firing order, of fuel pumping means for each of said cylinders, means responsive to the compression pressure in the respective cylinders for controlling the amount of fuel delivered by said pumping means to the respective cylinders, means driven by said engine for effecting communication between said pressure responsive means and the respective cylinders when said cylinders are under compression.

THOMAS A. BANNING, JR.

CERTIFICATE OF CORRECTION.

Patent No. 2,213,683.

September 3, 1940.

THOMAS A. BANNING, JR.

It is hereby certified that error appears in the printed specification of the above numbered patent requiring correction as follows: Page 4, second column, line 4, before the word "compression" insert --compression in the--; and that the said Letters Patent should be read with this correction therein that the same may conform to the record of the case in the Patent Office.

Signed and sealed this 5th day of November, A. D. 1940.

Henry Van Arsdale,

(Seal) Acting Commissioner of Patents.
